[57] CLAIM

The ornamental design for a brake for roller skate or the like, substantially as shown and described.

DESCRIPTION

FIG. 1 is a perspective view of a brake for a roller skate or the like showing my new design;

FIG. 2 is a rear elevational view thereof;

FIG. 3 is a left side elevational view thereof;

FIG. 4 is a bottom plan view thereof; and,

FIG. 5 is a perspective view of a modified form of the brake pad member of the design shown in FIGS. 1 through 4.
